UNITED STATES PATENT OFFICE.

GUSTAV BLUMBERG AND JOHN A. BUTKUS, OF BALTIMORE, MARYLAND.

ELECTRIC CLOCK.

1,312,946.

Specification of Letters Patent. Patented Aug. 12, 1919.

Application filed December 23, 1915, Serial No. 68,415. Renewed February 1, 1919. Serial No. 274,564.

To all whom it may concern:

Be it known that we, GUSTAV BLUMBERG and JOHN A. BUTKUS, citizens of the United States, residing at Baltimore, in the State of Maryland, have invented certain new and useful Improvements in Electric Clocks, (Case F;) and we do hereby declare the following to be a full, clear, and exact description of the invention, such as will enable others skilled in the art to which it appertains to make and use the same.

Our invention relates to electric clocks.

One object of our invention is to provide an electric clock in which the time train can be readily disconnected from the electro-magnetic mechanism, so that the time train can be removed for renewal, repair and adjustment.

A further object of our invention is to provide a circuit closer for use with our improved clock, which circuit closer shall be so constructed that the instant at which the circuit is broken by the circuit closer can be varied by a simple adjustment, in which the force with which the contacting surfaces come together may be varied, and in which the portions of the contacting surfaces which come together may be varied so as to provide new contacting surfaces when said surfaces wear.

These and other objects of our invention will be explained in the following specification, reference being had to the accompanying drawings in which:

Figure 1, is a front view of the mechanism of our improved clock, the circuit closer being in the closed position, certain features of the time train and the source of electricity being omitted;

Fig. 2, is a side view of the parts shown in Fig. 1, looking in the direction of the arrow 2 in said figure, certain features of the time train therein shown, being omitted;

Fig. 3, is a front view of certain features of our improved clock, the front plate of the time train and other features thereof being omitted;

Fig. 4, is a front view of the electro-magnetic mechanism of our improved clock;

Fig. 5, is a side view of Fig. 4, looking in the direction of the arrow 5 in said figure;

Fig. 6, is a front view of the time train detached from the electro-magnetic mechanism, certain features of the time train, including the ratchet wheel 28, being omitted;

Fig. 7, is a side view of the parts shown in Fig. 6, looking in the direction of the arrow 7 in said figure;

Fig. 8, is a view of a coupling pin which is used for a purpose hereinafter explained;

Fig. 9, is a bottom view of the circuit closer, looking in the direction of the arrow 9, in Fig. 1;

Fig. 10, is an enlarged view of part of our circuit closer; and

Fig. 11, is a view of the wire attached to the pallet of the escapement, looking in the direction of the arrow 11, in Fig. 7.

Fig. 12, is a diagram of the connections of my improved clock.

In the drawings:—
15 and 16 represent respectively the front and rear plates which support the time train of our improved clock. To the rear plates 16, three studs 17—17—17 are riveted. The front ends of these studs are reduced in diameter and pass through holes in the front plate 15. The end portions of the studs 17 are provided with threads and nuts 18—18—18, screwed on said threads, secure the front plate 15 to the studs 17. Bearing pieces such as 19—19 secured to the front and rear plates 15 and 16 of the clock train support the pintle 20 to which the pallet 21 is attached.

The wire 22, (see Figs. 7 and 11), is secured to the pintle 20. It extends downwardly and toward the rear and is provided with a fork 23, which is adapted to embrace the pendulum wire 24. The pendulum wire 24 is secured at its upper end in a bracket 25, and the latter is secured to the leg 26 of the frame of the electro-magnetic mechanism, hereinafter referred to.

The time train is formed of any approved combination of gearing, and to the last pintle 27 of the time train a ratchet wheel 28 is secured in any approved manner. The

pintle 27 and all other pintles of the time train are revolvably mounted in holes provided in the plates 15 and 16, and said pintles are provided with the usual shoulders 5 to prevent side play. Revolvably mounted upon the pintle 27, there is provided a soft iron armature 29, suitable shoulder bearings being provided on the pintle 27 to prevent side play of said armature 29. A spring 30, 10 connected to screws 31 and 32 secured to the armature 29 and the back plate 16 respectively, serves to give the armature 29 a tendency to revolve in the direction of the arrow 33 in Fig. 3. A pawl 34 secured to 15 the armature 29 is kept in engagement with the ratchet wheel 28 by the spring 35, which is also secured to the armature 29.

Hence, it is evident that if the armature 29 is moved in the direction of the arrow 20 33, the pawl 34 will cause the ratchet wheel 28 to revolve in the same direction and thus move the pintle 27. The minute hand of the 25 clock is to be attached to the pintle 27, and the hour hand of the clock is to be attached to a sleeve revolvably mounted on the pintle 27 and geared to said pintle in any approved manner. Said hands and gearing being old and well-known in the art have not been illustrated and will not be further referred to.

30 In order to prevent any movement of the pintle 27 in a direction opposite to the arrow 33, we provide the pawl 36, which is secured to the pintle 37 and the latter is revolvably mounted in plates 15 and 16. The 35 pawl 36 is so shaped that its weight will normally keep its point 38 against the teeth of the ratchet wheel 28.

The electro-magnetic mechanism of our improved clock is constructed as follows:—
40 We provide a cast iron yoke 39 which has two downward extensions 40—40 provided with slots 41—41. To the yoke 39, we secure magnet cores 42 and 43 by screws such as 44. Each of said magnetic cores is provided with 45 a pair of magnet heads 45—45 and between said heads, coils of insulated wire, one of which is shown at 46, are wound.

Secured to the yoke 39 by screws such as 47, are the portions 48—48 of the frame of 50 the electro-magnetic mechanism. Extending forwardly and downwardly and formed integrally with the portions 48—48 are two portions 49—49, which terminate at their ends in two downwardly extending portions 55 50—50, and the latter are joined together at their ends by the portion 51. Forwardly extending lugs 52—52 are formed integrally with the portions 50—50, and each of said lugs is provided with a slot, one of which is 60 shown at 53, in Figs. 2 and 5, for a purpose hereinafter explained.

At the junctures of the portions 50—50 with the cross piece 51, lugs 54 and 55 are provided. Each of said lugs is provided 65 with a central hole in which an insulating

bushing is placed. Insulating washers 56—56—56 are placed on the front of the lugs 54 and 55, and on the rear of the portions 50—50.

The post 57 is provided with a reduced 70 portion 58 which passes through the insulating bushing on the interior of the lug 55, the washers 56—56, one of the connectors 59, and on the ends of the reduced portion 58, nuts such as 60—60 are threaded which 75 serve to keep the post 57 and the corresponding connector 59 in place.

A screw 61 has a threaded portion which fits in a thread provided in the post 57. The screw 61 has a smooth body portion between 80 its head and the post 57 upon which is revolvably mounted the insulating lever 62.

Referring to Fig. 10, and especially to the full lines in Fig. 10, it will be noted that the lever 62 is provided with a portion 85 63 extending to the left of the screw 61, with a portion 64 substantially concentric with the screw 61, with a notch 65 in the concentric portion 64 and with a portion 66, which is also concentric with the screw 61 but 90 closer thereto than is the portion 64. A notch such as 67^a is provided between the concentric portions 66 and the rightwardly extending arm 67 of the lever 62. A screw 68 is threaded in the end of the arm 67, and 95 a screw is provided with a body portion for a purpose hereinafter explained.

A link 69 is provided, which is revolvably mounted at its upper end upon the pin 70. The pin 70 fits snugly in a hole provided 100 in the armature 29 and, (as shown in Fig. 8), the pin 70 has a cylindrical portion 71 adapted to fit in a hole in the armature 29 and a large cylindrical portion 72^a upon which the link 69 works. The pin 70 is provided with a slot through the portions 71 and 72^a so that the portion 71 will snugly fit the hole in the armature 29 and so that 105 said pin can readily be removed therefrom when the time train is to be disconnected 110 from the electro-magnetic mechanism.

The lower end of the link 69 is provided with a slot 72 which embraces the body portion of the screw 68. At its lower portion, the link 69 is provided with a stud 73 upon 115 which is mounted a cam 74 formed integrally with a lever 75.

The lug 54 is provided with a hole and an insulating bushing is secured in said hole. A screw having a head 76 has its body portion passed through the bushing in the lug 54 and the insulating washers 56—56 on the front of said lug and on the rear of the juncture of the portions 50—50 and cross piece 51. The rear end of said screw is 120 threaded the same as is shown at 58 in Fig. 2 with reference to the threaded portion of the post 57, and on said threaded portion is mounted a connector 59, which is secured in place by nuts similar to 60—60, shown in 125 130

Fig. 2. The connectors 59—59 are each formed of two strips of flat metal which are bent as shown in Fig. 2, and lie together substantially throughout their length. The 5 front ends, as at 77, of the connectors 59—59 are beveled as shown in Fig. 2.

Between the head 76 and the front washer 56 on the lug 54 there is clamped the portion 78 of the support for the spring 79 of 10 the contact maker.

Two outwardly extending portions 80 and 81 are formed integrally with the portion 78. Two prongs 82—82 are formed integrally with the portion 81, and a rightwardly extending portion 83 between the prongs 82—82 is formed integrally with the portion 81. The portion 82 is provided with a threaded hole in which works the threaded portion of the screw 84, the point of which 20 rests against the spring 79 and serves to adjust the pressure produced by the free end of said spring. A slot 85, cut in the portion 83, through the hole in which is threaded the screw 84, provides means for preventing 25 the inadvertent loosening of the screw 84.

Two prongs, in all respects similar to the prongs 82—82, and one of which is shown at 86, in Figs. 1 and 3, are formed integrally with the portion 81. The portions 80 and 30 81 are provided with holes in line with each other, in which is slidably mounted the screw 87. The screw 87 is provided with an enlarged portion 88 having a slot in which is soldered the wide portion 89 of the spring 35 79. The enlarged portion 89 slides between the prongs 82—82 and 86—86 by which means the spring 79 is prevented from turning from the position shown in the figures. A spring 90 is placed upon the screw 87 between the portion 80 of the support and the 40 enlarged portion 88 of said screw, and said spring gives said screw a normal tendency toward the right, which is resisted by the nut 91.

45 The front end of the spring 79 is provided with a curved portion 92 and a piece of platinum 93 is soldered upon said curved portion, as shown in Fig. 1. The piece of platinum 93 is adapted to contact with the piece of 50 platinum 94 secured in juxtaposition upon the post 57.

Two portions 95—95, (see Figs. 4 and 5), which extend upwardly and forwardly, are formed integrally with the portions 48—48 55 and the portions 95—95 are connected by the upwardly extending portions 96—96. From the juncture of the portions 96—96, the leg 26 extends backwardly and is provided with a foot 97 having a screw hole 98.

60 The mechanism of our improved clock is to be attached to the case by screws passing through the slots 41—41 and the hole 98. A riser 99 is provided at the juncture of the 65 portions 96—96 for the back plate 16 of the time train to rest upon as shown in Fig.

2. The riser 99 is provided with a threaded hole in which is screwed the threaded portion 100 of a wing screw 101.

The back plate 16 of the time train (see Fig. 6), is provided with a slot 102 for the 70 reception of the threaded portion 100 of the wing screw 101 and with two notches formed by the edges 103—103 and 104—104. The edges 104—104 fit against the faces 105—105 of the lugs 52—52 and the edges 103—103 75 extend into the slots 53—53.

Our improved clock is connected as follows:—

The inside ends of the coils surrounding the cores 42 and 43 are joined together. The 80 outside end of the coil surrounding the core 43 is connected to the post 57. The outside end of the coil surrounding the core 42 is connected to a source of electricity and the other terminal of said source is connected 85 to the screw 76.

Hence it is evident that if a piece of wire or sheet metal is introduced between the beveled edges 77 of one of the connectors 59 and then touched to the other connector 59, the 90 circuit will be closed and the magnetic cores 42 and 43 will attract the armature 29 and pull it around in a direction opposite to the arrow 33, in Fig. 1, until it assumes a position in which the magnetism of said cores 95 can no longer move said armature.

It is evident that if the maximum movement of the armature 29 is to be obtained, during the operation of our improved clock, from the attraction of said armature, that 100 the circuit must be opened when the armature has reached the position with reference to the cores just described, so that the inertia of said armature can carry it beyond said position.

Hence in adjusting our improved clock, we place a piece of metal between the connectors 59—59 and when the armature 29 has ceased moving under the influence of the magnetism of the cores 42 and 43, and 110 while said cores are still magnetized we move the lever 75 attached to the cam 74 in either direction, so as to move the screw 68 in the lever 62 either upwardly or downwardly, until the face 106 of the lever 62 115 between the concentric portions 64 and 66, acts sufficiently upon the curved portion 92 of the spring 79 as to separate the platinum contact 93 from the platinum contact 94. The pressure of the curved portion 92 can 120 be regulated as desired, by the screw 84 and the position of the contact 93 with reference to the contact 94 can be adjusted by turning the nut 91.

When it is desired to remove the time 125 train from the electro-magnetic mechanism, the pin 70 is removed from the armature 29, the wing screw 101 is unscrewed and removed, then the back plate 16 can be removed, from the slots 53—53.

The operation of our improved clock is as follows:

The parts being in the position shown in Fig. 1, the platinum contacts 93 and 94 will be in electrical connection with each other, a current of electricity will circulate through the coils surrounding the cores 42 and 43, and the armature will be attracted so as to move in the direction opposite to the arrow 33 in Figs. 1 and 3. As the armature 29 moves, the link 69 will be drawn upwardly and the cam 74 acting against the body of the screw 68 will move the lever 62 in a counter clockwise direction until the face 106, (see Fig. 10), strikes the curved portion 94 of the spring 79 and separates the platinum contacts. The inertia of the armature 29 and attached parts will carry said armature to the position shown in Fig. 3, (it being understood that the armature 29 is so related to the magnetic cores 42 and 43 that it can freely pass said cores), and the curved portion 94 of the spring 79 will drop into the notch 65 of the lever 62, and hold said 20 lever in the position shown in Figs. 3 and 10, when the link 69 moves downwardly as hereinafter explained. When the lever 62 is moved into the position shown in Fig. 3, as just described, the end of said lever 63 30 is provided and so located as to strike the spring 79 and prevent the lever 62 from being moved so far in a counter clockwise direction by its inertia, as to move the notch 65 beyond the curved portion 94 of the 35 spring 79.

The spring 30 then acts upon the armature 29 and moves it and the ratchet wheel 28 in the direction of the arrow 33, in Fig. 3. This motion continues until the top 107 of 40 the slot 72 strikes the body of the screw 68 and moves it from the position shown in Fig. 1, to the position shown dotted in Fig. 10. Then the pressure of the spring 79 acting on the face 106 of the lever 62 forces said 45 lever rapidly to the position shown in Fig. 1, thus permitting the pressure of the spring 79 to bring the contact 93 into electrical connection with the contact 94 so as to permit a current of electricity to circulate in the 50 coils surrounding the cores 42 and 43. This starts a new operation of the armature 29 and the succeeding operations are all carried out according to the cycle just explained.

We claim:—

55 1. The combination of a time train including a pintle and a ratchet wheel secured to said pintle, with an armature revolvably mounted on said pintle, a pawl mounted on said armature and engaging said ratchet 60 wheel, a spring for moving said armature in one direction and a source of electricity and an electro-magnet for moving said armature in the opposite direction, said armature and electromagnets being so disposed that when 65 said armature is over the poles of said mag-

nets, the attracting force of said magnets shall act upon said armature in a direction parallel to the axis of said pintle.

2. The combination with an armature, a source of electricity, an electric circuit and 70 a magnet in said circuit for moving said armature in one direction, of a lever, a link connected to said armature, a screw in said lever, a slot in said link embracing said screw, a cam revolvably mounted on said link 75 and extending across said slot whereby the working length of said slot can be varied, a spring for moving said armature in the opposite direction and a clock train moved by said spring. 80

3. The combination with an armature, a source of electricity, an electric circuit and a magnet in said circuit for moving said armature in one direction, of a lever, a link connecting said armature and said lever, a support having a bearing on which said lever is revolvably mounted, a fixed contact mounted on said support, a spring moved by said lever, a contact carried by said spring and adapted to make contact with 90 said fixed contact, a spring for moving said armature in the opposite direction and a clock train moved by said spring. 85

4. The combination of a time train including the pintle and a ratchet wheel secured 95 to said pintle, with an armature revolvably mounted on said pintle, a pawl mounted on said armature and engaging said ratchet wheel, a spring for moving said armature in one direction, a source of electricity and 100 an electro-magnet for moving said armature in the opposite direction, a lever moved by said armature and having a cylindrical surface provided with a notch and also having an approximately radial face adjoining said 105 cylindrical portion, a support having a bearing for said lever, a fixed contact mounted on said support, and a spring carrying a contact and bearing against said notch, whereby when said spring bears in said 110 notch said contacts shall be separated, and when said spring slides down said face said contacts shall come together. 110

5. The combination of a time train including a pintle and a ratchet wheel mounted on 115 said pintle, with an armature revolvably mounted on said pintle, a pawl mounted on said armature and engaging said ratchet wheel, a spring for moving said armature in one direction, a source of electricity and an 120 electromagnet for moving said armature in the opposite direction, a lever moved by said armature, a support provided with a fixed contact, a spring moved by said lever and having a contact adapted to touch said fixed 125 contact, and a slidable support for said spring. 125

6. The combination of a time train including a pintle and a ratchet wheel mounted on 130 said pintle, with an armature revolvably

mounted on said pintle, a pawl mounted on said armature and engaging said ratchet wheel, a spring for moving said armature in one direction, a source of electricity and an electromagnet for moving said armature in the opposite direction, a lever moved by said armature, a support provided with a fixed contact, a spring moved by said lever and having a contact adapted to touch said fixed contact, a slidible support for said spring, 10 and means for preventing said spring from turning.

In testimony whereof we affix our signatures.

GUSTAV BLUMBERG.
JOHN A. BUTKUS.
